H. Gross,

Extension Table,

N° 18636.

Patented Nov. 17, 1857.

UNITED STATES PATENT OFFICE.

HENRY GROSS, OF TIFFIN, OHIO.

EXTENSION-TABLE.

Specification of Letters Patent No. 18,636, dated November 17, 1857.

To all whom it may concern:

Be it known that I, HENRY GROSS, of Tiffin, in the county of Seneca and State of Ohio, have invented a new and useful Improvement in Extension-Tables; and I do hereby declare that the following is a full, clear, and exact description of the construction and operation of the same, reference being had to the annexed drawing, forming 10 part of this specification.

The nature of my invention consists in the construction of folding extension tables with two systems of hinged stretchers movable in opposite directions, and connected 15 by stay rods as hereinafter to be set forth.

In the drawing L L are the legs connected by cross pieces A, and having the frame B C, the pieces C forming the end of the table when closed.

20 E E and D D are the two systems of stretchers, hinged to cross pieces B and D', as shown in the drawing; one system at the extremities of the said pieces and the other in the middle thereof.

The two systems of stretchers are connected by the stay rods a a, running from the angle on one side of the lower system to the opposite angle of the upper system. These stay rods are embraced by a loop e to prevent lateral separation. 25 30

In operation, the table may be extended as desired, and will be perfectly braced in every position. This advantage is due to the upper system of stretchers E and the sliding stay rods a a connecting the two 35 systems of stretchers.

I claim—

The combination of the two systems of stretchers E and D with the stay rods a a, constructed and operating as, and for the 40 purposes set forth.

In testimony whereof I have hereunto signed my name before two subscribing witnesses.

HENRY GROSS.

Witnesses:

N. REDD,
WALTER BUNTING.
